UNITED STATES PATENT OFFICE

155,658

DESIGN FOR A SEWING THIMBLE

Sarah Uribe, Los Angeles, Calif.

Application May 7, 1948, Serial No. 146,218

Term of patent 14 years

(Cl. D3—19)

To all whom it may concern:

Be it known that I, Sarah Uribe, a citizen of the United States, and resident of Los Angeles, county of Los Angeles, State of California, and whose post office address is #1052 S. Westlake Ave., Los Angeles 6, California, have invented a new, original, and ornamental Design for a Sewing Thimble, of which the following is a specification, reference being had to the accompanying drawing, forming a part thereof.

Fig. 1 is a top plan view of a sewing thimble showing my new design.

Fig. 2 is a side elevational view of the thimble.

Fig. 3 is a bottom plan view of the thimble.

Fig. 4 is a front elevational view of the thimble.

I claim:

The ornamental design for a sewing thimble, as shown.

SARAH URIBE.
